UNITED STATES PATENT OFFICE.

WARREN C. PATTERSON, OF POTTSVILLE, PENNSYLVANIA, ASSIGNOR OF ONE-HALF
TO JOHN F. JOHNSON, OF LEWISBURG, PENNSYLVANIA.

SAFETY ATTACHMENT FOR LOCOMOTIVES.

Application filed December 4, 1922. Serial No. 604,914.

To all whom it may concern:

Be it known that I, WARREN C. PATTERSON, a citizen of the United States, residing at Pottsville, in the county of Schuylkill and State of Pennsylvania, have invented a new and useful Improvement in Safety Attachments for Locomotives, of which the following is a specification.

This invention relates to safety attachments for locomotives.

The object is to provide an attachment to be secured in position on each side of a locomotive in a manner to support the drive rod or connecting rod, when either rod becomes broken or detached from the wrist pin or pins of the drive wheels while the locomotive is under way, and thus avoid damage to the road bed or to the engine or derailment of the latter when such mishap occurs.

In carrying out the invention, I provide a device which may be secured in position beneath the running board at each side of the locomotive, and between any two of the 25 drive wheels, whether the locomotive has only two or more drive wheels, and on the outside thereof, the said attachment having vertically disposed bars with a front to rear passageway of sufficient width to accommodate the said drive and connecting rods in side-by-side relation to each other, the said passageway being of sufficient height to permit the vertical movements of the rods while running, the vertical bars being joined by 30 upper and lower cross plates or abutments to prevent the broken bars from falling to the track below or from damaging the cab or boiler or other parts above.

A full and complete understanding of the 40 invention may be obtained from a consideration of the following detailed description, taken in connection with the accompanying drawing forming a part of this specification; it being understood that while the 45 drawing shows a practical form of the invention, the latter is not confined to strict conformity with the showing thereof, but may be changed or modified so long as such changes or modifications mark no material 50 departure from the salient features of the invention, as specifically pointed out in the appended claims.

In the drawing, in which similar reference characters designate corresponding 55 parts throughout the several figures.

Fig. 1 is a side elevation of a portion of a locomotive, showing the improved safety device in position thereon;

Fig. 2 is a detail horizontal sectional view taken on the line 2—2 of Fig. 1;

Fig. 3 is a detail perspective view of the attachment.

Many serious accidents and oftentimes derailment of the locomotive are caused by the breakage of the drive rod running from the cross head to one of the drive wheels, or by the breakage of the horizontally disposed connecting rod which joins the two or more drive wheels, the broken member being driven with tremendous power against the road bed sufficiently to lift the side of the locomotive and topple the same over sideways. The same result often happens when the boxings surrounding the wrist pins become broken or damaged, or the wrist pin itself is broken, and the present simple, cheaply-manufactured and easily installed safety attachment is designed to prevent such accidents in the following manner.

The invention comprises a simple, cage-like frame consisting of four corner posts or bars 1, each of which is preferably angular in cross section, as shown in Fig. 2, for the purpose of imparting great strength with minimum lightness.

The corner posts 1 are joined at their lower ends by a base plate or platform 2, the outer corners of said posts being preferably flush with the corners of said platform and integrally joined thereto, the entire device being in the form of a casting or a forging, the several parts being capable of being welded together.

The upper ends of the posts 1 are joined to a rectangular cap 3 constituting an attaching plate of greater dimensions than the base plate 2, the four projecting corners being provided with bolt openings 4, through which are passed bolts 5 for securing the device beneath the running board 6 of the 100 locomotive.

Beneath the attaching plate 3 and in spaced relation to the same, is another plate or platform 7 joined to the corner posts in the same manner as the base plate 2, the two plates being preferably formed solid though the same may be of flanged construction.

When the attachment is secured to the running board 6, as shown in Fig. 1 of the 110

drawing, the four corner posts 1 are located just outside of the front and rear drive wheels 8, as shown in Fig. 2, the longitudinal vertical axis of the device being coincident with the space between the flanges of said wheels. While the drawing shows a locomotive with but two drive wheels, as in some types of locomotives, it will be understood that more than one of the attachments 10 will be used on a side where a greater number of drive wheels are employed.

The length of the posts 1 is such that when the attachment is secured in position, a horizontal line intersecting the axes of the drive wheels passes through the device exactly midway between the upper and lower plates or platforms 7 and 2 respectively, the distance between said plates being ample to allow of the rising and falling movements 20 of the drive rod 9 and the connecting rod 10, without danger of either contacting with the said plates, as long as the rods and their wrist pins hold.

When breakage occurs, it will be seen that 25 either of the rods is prevented from contacting with the ground by reason of the lower plate 2 which will support the same, and at the same time allow of the gyrating movement of the rod caused by the remaining intact wrist pin, and in like manner both rods are prevented from contacting with and injuring any of the parts of the locomotive located above, by reason of the interposed, upper plate or platform 7.

30 While the attachment is shown and described as being in the form of a forging or a casting, with all the parts thereof formed integrally, it is to be understood that the same may be of other formations, such, for instance, as by forming the corner posts 1 separately of bar iron or of angle iron, and suitably connecting them to the attaching plate 3 at the top, the bottom plate or platform 2 and the intermediate plate or 35 platform 7 by means of rivets or bolts in any desired manner without departing from the spirit or scope of the invention.

From the foregoing it will be seen that a simple device has been provided for the

purpose stated, which may be easily and 50 cheaply manufactured and installed in position upon either side of a locomotive without interfering with any of the working parts and without adding materially to the weight of the locomotive, the device effectually acting to hold and support broken drive or connecting rods and prevent their doing any damage while the engine is being brought to a standstill.

What is claimed is:—

1. A safety attachment for locomotives, comprising a means adapted to be secured to the side of the locomotive and to surround the drive rod and connecting rod while permitting full movements of these 65 parts, said means constituting a support for the rods to prevent their falling to the ground or striking the locomotive in the event of any breakage.

2. A safety attachment for locomotives, comprising an open frame having means at its upper end for attachment to the running board of the locomotive and having a passageway longitudinally of the locomotive for the free rotary and reciprocatory movements 70 of the drive and connecting rods therethrough, said frame having means to support the said rods in the event of breakage.

3. A safety attachment for locomotives, comprising a frame having an upper attaching plate adapted to be bolted on either side of the locomotive and to the underside of the running board at a point intermediately between the drive wheels, depending corner posts carried by said plate, integral upper and lower abutment plates carried by the said posts, said posts being spaced apart sufficiently to receive the drive and connecting rods of the locomotive, the said abutment plates being spaced one above the other sufficiently to permit of the normal movements of said rods and to prevent their contacting with the roadbed or with the locomotive in the event of breakage.

In testimony, that I claim the foregoing as my own, I have hereto affixed my signature.

WARREN C. PATTERSON.
